C. H. BESNARD.
BUILDING CONSTRUCTION.
APPLICATION FILED OCT. 24, 1919.

1,419,126.

Patented June 13, 1922.

UNITED STATES PATENT OFFICE.

CHARLES HENRI BESNARD, OF PARIS, FRANCE, ASSIGNOR TO JULIEN PIERRE
BERTEAND BESSONNEAU, OF PARIS, FRANCE.

BUILDING CONSTRUCTION.

1,419,126.

Specification of Letters Patent. Patented June 13, 1922.

Application filed October 24, 1919. Serial No. 333,117.

(GRANTED UNDER THE PROVISIONS OF THE ACT OF MARCH 3, 1921, 41 STAT. L., 1313.)

To all whom it may concern:

Be it known that I, CHARLES HENRI BESNARD, a citizen of the French Republic, residing at 16 Rue de Bagneux, Paris, France, 5 have invented certain new and useful Improvements in Building Construction, (for which I have filed application for patent in France on April 29, 1918, patent of Addition No. 20,927), of which the following is a 10 specification.

This invention relates to improvements in roofing and more particularly to the type provided with transparent portions to permit light to penetrate the roof.

15 A primary object of the present invention is to provide a roof formed of elements which may be prepared in a factory, and then shipped to the place of use and rapidly assembled.

20 A further object of the invention is to provide a roof formed of trussed cement elements which may deform slightly in use without liability of causing leaks.

25 A further object of the invention is to provide a roof formed of cement elements which may be connected together by means permitting the quick disassembling of the parts, so that a roof of a building formed of the improved elements may be rapidly taken apart, 30 when necessary.

With the foregoing objects outlined, and with other objects in view which will appear as the description proceeds, the invention consists in the novel features hereinafter described in detail, illustrated in the accompanying drawing and more particularly pointed out in the appended claims.

Referring to the drawing:

Figure 1 is a perspective view of a portion 40 of a roofing of "shed" form.

Fig. 2 is a transverse sectional view of the same.

Fig. 3 is a top plan view of the construction shown in Figure 2.

45 The roofing is constructed by forming the latter by means of trussed cement elements assembled together by simple rabbeting and self-supported without a framing.

50 The said elements consist of a very wide gutter *h* forming a girder, the edges of the two raised sides of which terminate in substantially cylindrical members *i*, *i*. A large slab *j* apertured to receive panes of glass, is

placed on one of the edges of the gutter *h*, and its lower edge is provided with a cavity 55 or socket which fits exactly with the shape of the member *i* of the said edge. The said slab *j* constitutes one of the elements of the steepest slope of each bay in the roof.

A large rubble-floor slab *k* is also provided 60 which forms the large slope of the shed and rests partly on one edge *i* of gutter *h* and partly on the perforated slab *j* where it is supported by the corbel-shaped moulding *j'* provided in the upper part of said slab. 65 The lower edge of the slab *k* is also provided with a cavity or socket to engage one of the members *i*.

The slabs *j* and *k* are provided at their side edges with cheeks *l* which form solid 70 masses of equal resistance and which impart to said slabs a high resisting power to flexion in their longitudinal direction.

The said cheeks *l* are covered with ridge-tiles consisting of mouldings which form a 75 capping.

In order to facilitate the fixing and ensure the bracing of the roof the following arrangement has been adopted:—

Full rubble-floor slabs *k* have exactly half 80 the width of the perforated slabs *j*. They are superimposed one upon the other whilst overlapping the joints.

Each gutter is capable of forming a girder, 85 in which case it is made of one piece along its full length; or when the span is too great its section is reduced and it rests clamped upon an independent girder of iron, cement, wood, etc., or other suitable material. In such case, in order to ensure the tightness of the joints, the same procedure is adopted as indicated in the above-mentioned application i. e., a thin cement channel covering the grating is cast inside the gutter.

90 It will be noted from Figures 2 and 3 that the upper edges of the slabs *j*, *k* are provided with substantially vertically extending flanges *m*, which are separated by a groove *n*. This construction permits the use of a demountable ridge tile adapted to cover the 100 joint at this point and assure tightness thereof. It will also be noted that the joint at the point *j'* is formed by curved surfaces, so that the slabs may ride on one another at these joints when the slabs expand or contract.

105 From the foregoing it will be seen that the

joints of the different roof elements are provided by curved surfaces which permit play of the various elements without reducing the strength of the roof panels.

5. It will also be noted that the extreme upper surfaces of the member *i* are arranged above the lower edges of the slabs so that water flowing down the slabs will enter the gutter without liability of seeping through 10 the joints at the lower ends of the slabs.

The above described arrangements are given as exemplifications only; the shapes, dimensions, constituent materials, details of execution and applications may be varied 15 without departing from the distinguishing features of the invention.

Having now particularly described and ascertained the nature of my said invention and in what manner the same is to be performed, I declare that what I claim is:—

20 1. In a demountable concrete roof, a plurality of gutters spaced apart and each having opposite side walls terminating in upper curved surfaces, a plurality of slabs arranged at angles to each other and having their upper ends engaging one another, and curved surfaced grooves provided in the lower edges of said slabs and engaging the upper curved edges of the sides of the gutters.

25 2. A roof of the kind defined by claim 1 in which the engaging surfaces at the upper edges of the slabs are curved to permit relative movement of the slabs.

3. A roof of the kind defined by claim 1 in which the side edges of each slab are provided with upwardly extending longitudinally disposed flanges.

4. A roof of the kind defined by claim 1 in which the upper ends of the slabs are provided with upwardly extending spaced flanges adapted to be covered by a ridge cap, the tongue of which is adapted to project into the space between said flanges.

5. In a demountable concrete roof, a plurality of combined girders and gutters spaced apart and each provided with upwardly extending sides terminating in substantially cylindrical edges, a series of imperforate slabs arranged side by side and having their lower edges provided with curved surfaced grooves engaging the edge at one of the sides of one of the girders, a series of apertured slabs arranged at angles to the imperforate slabs and having their lower edges provided with curved surfaced grooves engaging the edge of one of the sides of the other girder, the extreme upper surfaces of said substantially cylindrical edges being located at a height above the lower edges of said slabs, the upper ends of said imperforate slabs being provided with curved surfaces, and the upper ends of the apertured slabs being provided with curved surfaces which engage the curved surfaces at the upper ends of the imperforate slabs.

In testimony whereof I affix my signature.
CHARLES HENRI BESNARD.

Certificate of Correction.

It is hereby certified that Letters Patent No. 1,419,126, granted June 13, 1922, upon the application of Charles Henri Besnard, of Paris, France, for an improvement in "Building Construction," were erroneously issued to Julien Pierre Bertrand Bessonneau, as assignee of the entire interest in said invention, whereas said Letters Patent should have been issued to the inventor, said *Besnard*, and *Julien Pierre Bertrand Bessonneau*, said Bessonneau being assignee of *one-half* interest only in said invention, as shown by the records of assignments in this office; and that the said Letters Patent should be read with this correction therein that the same may conform to the record of the case in the Patent Office.

Signed and sealed this 11th day of July, A. D., 1922.

[SEAL.]

KARL FENNING,

Acting Commissioner of Patents.
